UNITED STATES PATENT OFFICE.

RENÉ THURY, OF GENEVA, SWITZERLAND, ASSIGNOR TO THE COMPAGNIE
DE L'INDUSTRIE ELECTRIQUE, OF SAME PLACE.

DYNAMO-ELECTRIC MACHINE.

SPECIFICATION forming part of Letters Patent No. 567,423, dated September 8, 1896.

Application filed August 5, 1895. Serial No. 558,183. (No model.) Patented in Switzerland June 28, 1892, No. 5,581; in France November 11, 1892, No. 225,578, and in Italy November 22, 1892, No. 33,019/312.

To all whom it may concern:

Be it known that I, RENÉ THURY, electrician, a citizen of the Republic of Switzerland, residing at Geneva, Switzerland, have 5 invented certain new and useful Improvements in Dynamo-Machines, of which the following is a specification.

Letters Patent for this invention have been granted to me in Switzerland under date of 10 June 28, 1892, No. 5,581; in France under date of November 11, 1892, No. 225,578, and in Italy under date of November 22, 1892, No. 33,019/312.

The objects of my invention are to increase 15 the efficiency of electric-current generators, and to effect economy in the cost of manufacture and in the cost of working or maintenance. In attaining these objects I aim to dispense with or reduce as much as possible the 20 loss due to hysteresis in the iron of the machine, and also to reduce to a minimum the energy expended in exciting the field-magnets.

In carrying out my invention I provide a circular magnet having an annular cavity in 25 which is a helix and also having an annular side opening whose opposite surfaces constitute the N and S poles.

The armature is in the form of a ring filling the annular side opening of the magnet 30 between the respective poles, and arms connect the armature-ring to a hub upon the driving-shaft. The armature is of the same polarity as the adjacent and inner plain face of the circular magnet, and becomes an ex- 35 tension of the N pole, except as hereinafter explained.

One pole-piece is made with alternate pro- 40 jections and spaces like a toothed wheel, and the adjacent and opposite pole-piece has a smooth surface and consists of laminated rings with a surface winding thereon. The space between these two surfaces constitutes the air-gap, which is reduced to a minimum between the adjacent surfaces and is aug- 45 mented between the teeth, so that the lines of force vary in intensity because of the alternately narrow and wide air-spaces, and the revolving ring-armature within the annular side opening of the magnet is exposed to al- 50 ternating magnetic influences that set up

electric currents, and these currents have differing ratios of intensity according to the form of winding upon the surface of the laminated rings and the speed of the armature and extent of the magnetic field. This wind- 55 ing may be serpentine and be placed upon the stationary pole in an alternating-current machine where no commutator is needed, or convoluted and placed upon either the stationary pole or the polarized armature in a 60 continuous-current machine employing a commutator, and the winding may be so arranged as to be of a monophased, biphased, or polyphased character, according to the quantity and intensity of the current desired. 65 I employ one exciting-coil, and the poles are of one polarity or sign throughout the entire revolution of the armature. This winding may be placed upon the stationary pole or upon the revolving armature. 70

With my improvement I employ only one exciting-coil, as the poles are of one polarity or sign throughout the entire revolution, the only change being in their intensity with regard to the different elements of the winding. 75

In the drawings, Figure 1 is a vertical cross-section. Fig. 1^a is a partial vertical cross-section showing the direction of lines of force by arrows, and Fig. 2 is a vertical longitudinal section illustrating my invention. Figs. 80 2^a, 2^b, and 2^c are vertical longitudinal sections of part of my machine, showing the respective positions of the armature in relation to the winding of flat coils. Figs. 3 and 3^a are dia- 85 grams of methods of winding, the diagram Fig. 3^a representing the directions of the currents in companion coils. Fig. 4 is a diagram of a method of winding for continuous currents. It is a well-known multipolar drum-winding. Fig. 5 is a vertical cross-section, 90 and Fig. 6 is a vertical longitudinal section, representing a machine similar to Fig. 1, but with the toothed surface and winding transposed. Fig. 7 is a vertical cross-section, and Fig. 8 is a vertical longitudinal section, rep- 95 resenting a machine having a Gramme armature of laminated rings with the opposite surfaces provided with convoluted winding and toothed surfaces to the respective poles that alternate with each other. Fig. 9 is a 100

section similar to Fig. 8, but in larger size, illustrating the direction of the magnetic lines; and Fig. 10 is a diagram of the method of winding the device of Figs. 7, 8, and 9, 5 and which may also be applied to the devices of the other figures shown. Figs. 1 to 3^a, inclusive, relate to alternating-current machines not employing a commutator; and Figs. 4 to 10, inclusive, refer to continuous-current machines employing a commutator.

The frame C is suitably supported and is of a rectangular figure and provided with two brackets, and the circular magnet M is connected to and supported by said brackets. 15 A peripheral ring or rim M' extends around the circular magnet M. The circular magnet M has an annular and central cavity for the winding or helix f and an annular side opening to receive the armature A². The constant pole N is part of the circular magnet and forms the inner face of the annular side opening and is plain and smooth, while the constant pole S forms the outer face of the annular side opening and part of the ring M'. 20 There are bearings across the open center of the circular magnet to carry the shaft of the wheel or polarized armature A², and said shaft is rotated by the pulley P. The armature A² is of the same N polarity as the adjacent plain face of the magnet, and is practically a continuation of said poles. 25

In Figs. 1 and 2 the face of the S pole consists of a laminated ring with a surface of serpentine or convoluted winding e, while 30 the face of the armature and working face of the N pole opposite the S pole consists of teeth d, like a toothed wheel. This machine is especially adapted to alternating currents.

The schema of the winding shown in Fig. 40 3 is that while similar portions of the serpentine wire pass opposite the teeth d the intermediate portions of the convolutions pass between the teeth. The winding shown in Fig. 3^a comprises a continuous surface of 45 wire in groups wound in opposite directions, so that the alternating magnetic actions set up currents throughout the coils. The wires opposite to the teeth are subjected to an energetic induction on account of the concentration of the magnetic induction in these 50 teeth due to the thinness of the air-gap at these places, while the wires that come opposite to the spaces between the teeth are subjected to a weak induction in the same direction, that is to say, in the direction weakening the current generated. The difference, however, is very large and the useful current being very strong can be advantageously utilized. The laminated rings facing one of 60 the poles are used to avoid the production of Foucault currents in the mass of the magnet-pole.

In order that the action of the lines of magnetic force upon the induced coils may be 65 well understood, I will proceed to successively explain the different positions of the toothed armature-surface in its relation to

the winding of the laminated surface. (See Figs. 1^a, 2^a, 2^b, 2^c, and 3^a.)

The groups I, II, III, and IV represent flat 70 coils of wire which have been formed on a suitable mandrel and thereafter applied and fixed upon the laminated surface, and these coils are connected to one another in series. The figures 1 2 3 and 3 2 1 indicate in these 75 figures the respective wire of each coil.

In the position shown in Fig. 2^a the right-hand portion of the coils II and IV and the left-hand portion of the coils I and III are crossed by lines of magnetic force and are 80 in action. An induction is therefore produced in the said wires and the return of the current takes place on the other side of the coil which at that time is inactive.

In the position shown in Fig. 2^b the lines 85 of magnetic force emanating from the teeth pass directly through the intervals left between the right and left hand portion of each coil. No other induction is produced than that one caused by the expansion of the lines 90 of magnetic force. It is very feeble and neutralizes itself completely.

In the position shown in Fig. 2^c the left-hand side of the coils II and IV are induced. The direction of the lines of magnetic force 95 not having been changed, the direction of the electromotive force remains the same. The current circulates in an inverse direction, the sides of the coils which are influenced being the opposite one with regard to 100 Fig. 2^a. I have therefore herein realized the sinusoid of the ordinary alternative machines. The induction thus produced is therefore the result of the displacement of the lines of force along the induced coil, which 105 displacement is caused by the rotation of the toothed wheel, while the total flux remains constant. The device claimed is therefore quite different in its effect from that of the dynamo-machines heretofore employed and 110 in which the induction is caused by the variation of the number of lines of force in certain parts of the magnetic circuit. These latter are the seat of hysteresis and Foucault currents, which lower the effect from that of 115 the dynamo-machines heretofore employed and in which the induction is caused by the variation of the number of lines of force in certain parts of the magnetic circuit. These latter are the seat of hysteresis and Foucault 120 currents, which lower the effect of the dynamo. They must be lamellated and are the more subject to violent vibrations, which rapidly disjoin the same.

In my improved machine the toothed wheel 125 is not lamellated because, as already stated, the flux is completely constant, and the surface at the opposite side of the air-gap, and upon which the induced coil is fixed, is smooth. In Figs. 5 and 6 these conditions 130 are reversed, the S pole face consisting of teeth d, like a toothed wheel, and the face of the armature—that is the N pole, opposite thereto—consisting of a laminated ring with

a surface of convoluted winding *e*, with the wires carried down to the commutator-bars D. This machine is especially adapted for continuous currents, the same passing through 5 the commutators D.

The laminated peripheral armature-surface is employed to avoid Foucault currents. I do not wish to make the entire armature mass in this manner, as the variations of 10 magnetic induction of the field are only felt in the part opposite to the teeth, while on the interior face this intensity is uniform, the internal part of the armature being only a prolongation of the pole N of the circular 15 magnet.

In Figs. 7 and 8 both N and S pole faces consist of teeth like a toothed wheel, while the armature consists of a laminated ring, with both internal and external faces provided with convoluted winding *e*, with the wires carried down to the commutator-bars D for a continuous-current machine. In these 20 Figs. 7 and 8 the armature-ring is provided with Gramme winding, and the internal face 25 of the S pole and external face of the N pole are alternately toothed (see Fig. 8)—that is, the teeth of one are opposite the spaces of the other. Without this alternation the induced 30 electromotive forces would annihilate one another in each spire of the ring.

The operation of the machine and its form of winding, as shown in Figs. 7, 8, 9, and 10, are as follows: The armature is a Gramme ring. The teeth of the two pole-faces are not 35 opposite to one another, but differentiate in order that the teeth of one pole-face may be opposite the recesses of the other. The winding-wires of the armature which are externally under the teeth return on the inner side 40 of the armature in the recesses, and vice versa. There is therefore induction in the wires opposite the teeth, the return of the current taking place by the wires opposite the recesses.

This machine may be considered as having 45 two air-gaps, one external and one internal, and both formed by a toothed surface and a smooth surface.

The winding shown in Fig. 10 illustrates the manner of winding the armature of Figs. 50 7, 8, and 9. The winding may be arranged for a monophased machine, for a biphased machine, or for a polyphased machine, the windings for the biphased and polyphased machines being in reality the duplicate and 55 triplicate of the monophased winding, wherein a second or third set of convolutions fill the empty spaces left in the middle of the convolutions of the other sets. A biphased winding is shown in Fig. 10. A monophased 60 winding is shown in Fig. 3.

The total resistance of magnetic circuit and air-gap is in my improvement kept constant in spite of the movement of one of the surfaces, and by placing an appropriate winding 65 close to the plain surface constituting one of the faces of the air-gap I get a current de-

pending upon the admitted conditions of speed and magnetic field, as in ordinary dynamos. The loss usually due to hysteresis is in my device concentrated on the plain surface, and only on a very thin film of said surface, in such a way that said loss is insignificant and unimportant. 70

In machines designed for generating alternate currents the convoluted winding is preferably employed in the part that does not revolve. By my improvement I attain great simplicity and dispense with many movable electric connections and the possibility of dispensing with commutators and brushes. 75 80

I claim as my invention—

1. In a dynamo-electric machine a circular magnet having an annular cavity and a helix therein and an annular side opening whose opposite surfaces constitute the N and S poles, 85 an armature-ring within the annular side opening and between the N and S poles, a shaft therefor and means for rotating said armature, the armature and one pole-piece consisting respectively of teeth-like projections and laminated rings with a flat surface winding directly upon the edge face of the laminated rings, substantially as set forth.

2. In a dynamo-electric machine, the combination with the magnetic poles, of a series of 95 laminated rings and a continuous surface of wire in groups wound in opposite directions as described, so that the alternating magnetic actions set up currents throughout the coils, substantially as specified. 100

3. In a dynamo-electric machine, the combination with the magnetic poles, of a series of laminated rings and a continuous surface of wire in groups wound in opposite directions as described, so that the alternating magnetic actions set up currents throughout the 105 coils, and a second set of groups similarly wound and intermediate to the first set of groups, substantially as specified.

4. In a dynamo-electric machine a circular 110 magnet having an annular cavity and a helix therein, and an annular side opening whose opposite surfaces constitute the N and S poles, one of said surfaces being plain and the other consisting of laminated rings with a flat convoluted surface winding directly upon the edge faces of the laminated rings, an armature-ring within the annular side opening and between the N and S poles, said armature having its surface that is opposite to the 115 flat convoluted winding made with alternate projections and spaces like teeth, substantially as and for the purpose set forth.

5. A dynamo-electric machine having a stationary pole-piece and a polarized armature, one of which consists of laminated rings with a flat convoluted surface winding directly upon the edge faces of the rings, and the other of which consists of alternate projections and spaces like teeth adjacent to 125 but opposite the convoluted surface windings so that the air-gap is reduced to a minimum 130

between the surface winding and end faces of the projections, and is augmented in the space between the projections or teeth so that the magnetic induction varies with the relative position of the opposing surfaces, substantially as specified.

5 In testimony whereof I have signed my

name to this specification in the presence of two subscribing witnesses:
